BALL AND RUNWAY TOY

Otis L. Gomer, Clearwater, Fla.

Application May 8, 1959, Serial No. 55,845

Term of patent 14 years

(Cl. D34—15)

Fig. 1.

Fig. 2.

Fig. 3.

Figure 1 is a perspective view of a ball and runway toy showing my new design.

Figure 2 is a front elevational view.

Figure 3 is a view partly in section taken on line 3—3 of Figure 2.

The dotted line portion is shown for illustrative purposes only.

I claim:

The ornamental design for a ball and runway toy, as shown.
